DESIGN FOR A SERVICE TRAY SUPPORTING BRACKET

Wallace A. Cozart and William A. Uttz, Sr.,
Fort Worth, Tex.

Application January 8, 1936, Serial No. 60,479

Term of patent 14 years

To all whom it may concern:

Be it known that we, Wallace A. Cozart and William A. Uttz, Sr., citizens of the United States, residing at Fort Worth, in the county of Tarrant and State of Texas, have invented a new, original, and ornamental Design for a Service Tray Supporting Bracket, of which the following is a specification, reference being had to the accompanying drawing, forming part thereof.

The figure is a perspective view of the bracket, showing our design.

The dotted circular element, shown in dotted outline in the drawing, illustrates a tray which is used for an ash tray.

What we claim is:

The ornamental design for a service tray supporting bracket, as shown and described.

WALLACE A. COZART.
